RAZOR BLADE HOLDER

Urban E. Wild, Jr., Los Angeles, Calif.

Application September 24, 1956, Serial No. 43,052

Term of patent 3½ years

(Cl. D22—3)

Fig. 1 is a front and elevational view of a razor blade holder showing my new design.

Fig. 2 is a side elevational view thereof.

Figs. 3, 4, 5, 6, 7 and 8 are cross-sectional views as taken on the respective lines 3—3, 4—4, 5—5, 6—6, 7—7 and 8—8 of Fig. 2.

I claim:

The ornamental design for a razor blade holder, substantially as shown.
